STARTER JAW MESHING MECHANISM

Ralph M. Heintz, Cleveland, Ohio, assignor, by
mesne assignments, to Jack & Heintz Precision
Industries, Inc., Cleveland, Ohio, a corporation
of Delaware

Original application December 6, 1944, Serial No.
566,871. Divided and this application October
15, 1945, Serial No. 622,412

1 Claim. (Cl. 74—7)

1

This invention relates to jaw meshing mechanism for aircraft engine starter and the like and is a division of the co-pending application for a patent in the name of Ralph M. Heintz, Serial No. 566,871, for Starter jaw-meshing mechanism, filed December 6, 1944, and now abandoned.

The general object of the invention is to provide an improved jaw meshing mechanism for automatically extending a starter jaw and engaging it with the engine to be started. More specifically the object of the invention is to provide means for positively and rapidly extending the starter jaw as it begins to rotate so that it will always enter into complete engagement with the engine in a more satisfactory manner than in conventional arrangements. In order to accomplish these objectives it is a further object to provide a nut having frictional engagement with the starter jaw in combination with a threaded shaft rotatable within the nut for extending the nut and the jaw together when the starter begins to operate.

The invention will now be described in connection with the accompanying drawings in which:

Figure 1 is a fragmentary view in section taken along line 5—5 of Figure 1, showing a preferred form of jaw meshing mechanism constructed according to the present invention, the jaw being in retracted position;

Figure 2 shows the mechanism of Figure 1 with the jaw extended into cranking engagement with a co-mating engine jaw;

Figure 3 illustrates a modification, with the jaw retracted;

Figure 4 shows the modification of Figure 3 with the jaw extended; and

Figure 5 is a view in rear end elevation, partly in section, showing the gearing connection from the motor to the gear train.

Referring first to Figure 1 the numeral 1 refers to the starter generally having an electric motor 2 driving a gear train which ultimately produces rotation of a sun gear shaft 3 by means of an internal ring gear 4. All the elements of this gear train do not appear in Figure 1, it being necessary only to understand that the ring gear 4 is motor driven. The sun gear shaft 3 includes an integral sun gear 5 in mesh with a plurality of planet gears 6 on a planet carrier 7. The planet gears 6, preferably 3 in number, mesh with a ring gear comprising a plurality of internally toothed clutch plates in a clutch assembly 8. As shown in Figure 5, the motor 2 has an output driving gear 53 that meshes with a larger

gear 54 that is mounted on the same shaft to rotate a smaller gear 55 that meshes with a larger gear 56. Gear 56 is carried by the same shaft as a planetary gear 57 in the planetary gear carrier 58. Planetary gear 57 meshes with the internal ring gear 4. The clutch assembly 8 is similar in general to that shown and described in my Patent No. 2,303,637 issued December 1, 1942, and in Patent No. 2,271,640 issued February 10, 1942, wherein the so-called ring gear may be considered as normally stationary in the starter housing so as to drive the planet carrier when the sun gear rotates.

The planet carrier 7 includes as an integral part thereof a sleeve 10 mounted for rotation in a bearing 9 and having internal spline grooves 11 carrying a jaw member 12, the latter being externally splined to fit the splines 11. The jaw member 12 is thereby rotated for engine cranking purposes by means of the planet carrier 7 which is in turn driven by sun gear 5 which is integrally interconnected with the ring gear 4 so that the jaw member turns relatively slowly in relation to the speed of the sun gear which in turn rotates much more slowly than the motor 2.

The sun gear shaft 3 is mounted in bearings 13 and 14 and is provided at its outer end with spiral threads 15 of high pitch, the threads making an angle of approximately 45° with the shaft.

The inner end of shaft 3 contains a deep recess 16 terminating in an end wall 17 forming a spring seat. The jaw 12 has an inner or tubular end 18 surrounding a deep recess 19 terminating in a spring seat 20 and housed within the recess 19 is a compression jaw spring 21 having its inner end abutting a bearing support 22 for the bearing 14, and having its outer end bearing against the seat 20 to constantly urge the jaw member toward its extended position.

The jaw member 12 is provided with a central conical surface 24 receiving a cone nut 25 having an outer conical end 26 bearing thereagainst as shown. The cone nut 25 is internally threaded to fit the spiral threads 15, and is provided with an apertured abutment washer 27. A jaw return bolt 30 passes through the abutment 27 and is provided with a head 31 for retracting the cone nut and jaw member after a starting operation under the action of spring 21 which exerts a force superior to that of spring 21.

The direction and pitch of the spiral threads 15 are such that rotation of the sun gear shaft 3 within the nut 25 causes the latter to move along the shaft as a nut as long as it is restrained from rotation with the shaft by frictional engagement

with the jaw member. The spring 21 causes the jaw member to follow the nut 25 as the latter is extended on the shaft 3 until the jaw member becomes engaged and fully seated in its co-mating jaw member 12' on the engine. The outward travel of the nut 25 will then cease as soon as it loses its frictional engagement with the jaw member so that it is free to rotate with the shaft 3. A nut 33 on the bolt 38 serves both as an abutment for the spring 32 and as a stop to limit excessive outward movement of the parts inasmuch as it will ultimately come to bear against the end 34 of the shaft 3. The opposite end 35 of the shaft 3 constitutes a similar stop for the parts in their return movement so as to leave a clearance between the jaw member 12 and the starter housing when the jaw member is fully retracted.

The planetary gear ratio is such that the difference in rotational speeds between the sun gear and the planet carrier is much greater than the speed of sleeve 10 with respect to the housing, thereby providing a novel and rapid automatic means of traverse for extending the jaw member. When the starter motor begins to turn, the rotation of the shaft 3 screws the cone nut 25 outwardly against the compression of spring 32 from its position in Figure 1 to approximately the position shown in Figure 2 wherein it is free to slip within the jaw member 12 after the latter has engaged itself with the co-mating jaw 12' on the engine to be cranked. It will be appreciated that as soon as slippage occurs between the cone nut 25 and the jaw member 12 the cone nut will merely rotate with the sun gear shaft 3 without extending itself further, clearance being provided between the shaft end 34 and the stop nut 33, as shown in Figure 2, when the jaw is seated.

When the engine fires while the starter is still cranking, the jaw member 12 will experience the usual ratchet action by the rapidly revolving engine jaw, causing the jaw 12 to reciprocate in and out on the cone nut against the compression of the jaw spring 21. When the starter is switched off and stops revolving the jaw return spring 32 through the reaction of the bolt head 34 on the abutment washer 27 causes the cone nut to spin down to follow the inward motion of the jaw 12 each time the latter is cammed inwardly away from the cone nut by the revolving teeth on the engine jaw. In this manner the jaw 12 is finally returned clear of the engine jaw 12' where it is held by the action of the jaw return spring which exerts a force considerably in excess of the jaw spring 21. Vibration of the parts tends to cause further slippage between the cone nut and the jaw 12 to finally return the jaw to its fully retracted position shown in Figure 1.

Figure 3 illustrates a modified construction in which the jaw return spring is not required to oppose the main jaw spring, thereby having certain advantages over the arrangement of Figure 1 in that the relative strengths of the two springs are not critical to satisfactory operation. This consideration is of particular importance where the two springs develop different characteristics upon aging so that a jaw return spring initially strong enough to produce the desired action might age faster than the main jaw spring so as to later produce an impositive return of the jaw. In the embodiment of Figure 3 each spring functions independently so that their relative strengths and their relative rates of aging do not affect the operation of the mechanism as long as the springs are individually able to perform their separate functions.

In Figures 3 and 4 parts identical with Figures 1 and 2 are indicated by the same reference numerals. Thus it will be seen in Figures 3 and 4, as in the first embodiment, that the starter jaw 12 is splined for longitudinal movement in a driving sleeve 10 rotatable in a bearing 9, this sleeve constituting an integral part of a planet carrier 7 having planet gears 6 rotated by a sun gear 5 on a sun gear shaft 3 which is in turn driven by a ring gear 4. The starter jaw also has the previously described deep recess 19 in its tubular end 18 terminating in a spring seat 20. In this embodiment, however, the jaw spring 40 abuts a jaw spring retainer 41 carried by a cone nut 42 similar to the cone nut 25. As in the previous embodiment, the cone nut 42 has a conical end 43 having frictional engagement with a conical surface 44 on the jaw 12. A jaw return spring 45 is carried by a bolt 46 secured in the sun gear shaft, as shown, and having a head 47 seated against the bottom wall 17 of the deep recess 16. A keyed nut 48 provides an end abutment for the spring 45 and also acts as a stop to limit the extension of the cone nut and jaw member. A spring retainer 50 carried by an abutment washer 51, or the like, within the cone nut, provides an abutment for the inner end of the jaw return spring 45. The spring 45 and the spring retainer 50 extend within a recess 52 in the end of the sun gear shaft.

The parts are normally at rest as shown in Figure 3 wherein both the main jaw spring and the jaw return spring are under only slight compression. When the starter begins to rotate, the cone nut 42 is screwed outwardly as in previous embodiment, by reason of the difference in rotational speeds between the sun gear shaft 3 and the planet carrier 7. As the cone nut advances, it compresses the spring 45 and carries with it jaw spring retainer 41, jaw spring 40, and the jaw 12 so that the latter is brought into driving engagement with the co-mating engine jaw 12'. When the jaw 12 has engaged the jaw 12' so that it cannot extend any farther, the cone nut 42 will lose frictional engagement with the jaw 12 and will thereafter slip in the jaw without further travel, as in the previous embodiment. Such position of the parts is shown in Figure 4 wherein it will be seen that a slight clearance remains between the jaw return spring retainer 50 and the stop nut 48.

When the engine fires while the starter is still cranking, the jaw 12 will be rapidly cammed inwardly by the teeth on the rapidly revolving engine jaw 12' against the compression of jaw spring 40. Then, when the starter is switched off and has ceased to rotate, the force exerted by jaw return spring 45 against the inner end of spring retainer 50 will spin the cone nut 42 down the steep spiral threads on the shaft 3 until it again engages the jaw member 12 by the engine jaw 12' will in this manner thrust the starter jaw completely out of contact with the engine jaw, in which position it will be held by the cone nut. Under the constant return force exerted by the spring 45, vibration of the parts will tend to gradually retract the jaw 12 completely to its original position shown in Figure 3.

It will be noted that the above described retraction of the cone nut 42 in the embodiment shown in Figures 3 and 4 is not opposed by the jaw spring 40. The action of the spring 45 is in no way affected by the action of the spring 40, so

that the relative strengths of aging rates of the two springs is of no consequence to the satisfactory operation of the mechanism. Another advantage of this embodiment is that when the jaw is in returned, or rest, position both springs are in their most relaxed conditions, increased spring stress occurring only during operation of the starter.

In both of the above described embodiments the extension of the starter jaw is entirely automatic in response to the initial rotation of the starter for an engine starting operation; and is effective to bring the starter jaw into deep seated engagement with the engine jaw so as to avoid damage to the jaw teeth resulting from tip engagement only, which has been a rather common occurrence in prior art jaw meshing mechanism. The invention includes all such variations in construction and arrangement of parts as fall within the scope of the appended claim.

I claim:

In an engine starter having a planetary reduction gearing unit comprising a sun gear driving shaft and a driven planet carrier, an extendable jaw member splined in said planet carrier, a

conical friction surface in said jaw member, a cone nut having a complementary conical friction surface, a jaw spring carried by said cone nut and acting against said jaw member to urge said surfaces into frictional engagement, a recess in said sun gear shaft, a bolt carried by said shaft in said recess, a tubular spring retainer carried by said cone nut and surrounding said bolt in said recess, and a jaw return spring around said bolt within said spring retainer and bearing thereagainst to retract said cone nut and jaw member upon cessation of rotation thereof.
